UNITED STATES PATENT OFFICE

117,107

DESIGN FOR A COMBINED PHONOGRAPH, RECORD, AND RADIO CABINET

Eddy R. McDuff, Detroit, Mich.

Application June 28, 1939, Serial No. 85,728

Term of patent 7 years

To all whom it may concern:

Be it known that I, Eddy R. McDuff, a citizen of the United States, residing at Detroit, in the county of Wayne and State of Michigan, have invented a new, original, and ornamental Design for a Combined Phonograph, Record, and Radio Cabinet, of which the following is a specification, reference being made to the accompanying drawing, forming part thereof.

Fig. 1 is a perspective of the combined phonograph, record, and radio cabinet.

Fig. 2 is a front elevation of the same. The rear of the cabinet is plain and contains a conventional loud speaker at the top.

I claim:

The ornamental design for a combined phonograph, record, and radio cabinet, substantially as shown and described.

EDDY R. McDUFF.
